GARMENT

Eleanor Fligel, New York, N. Y.

Application March 7, 1945, Serial No. 581,519

7 Claims. (Cl. 2-93)

1

This invention relates to garments and has particular application to garments of the reversible type.

So far as I am aware, garments of the reversible type have heretofore been made by providing the outer face of the garment with one type of cloth, color or pattern and the inner face of the garment with a contrasting color, fabric or pattern, so that when the garment is turned inside out, it presents an entirely different appearance. These prior garments, however, were limited to only two different effects which they could produce and had the further disadvantage that they did not provide a uniformity of appearance for each effect unless their structures were made in a somewhat complicated manner.

It is the primary purpose of the present invention to provide a simply constructed, compound garment which can be manipulated readily to give four different contrasting effects. The garment may be aptly termed a four-in-one garment, capable of being readily transferred into any one of the four styles or contrasting effects at the option of the wearer.

The manner in which the above object is accomplished and the novel details of construction of the garment will be best understood from the following description when read in connection with the accompanying drawings which illustrate a coat or jacket embodying the invention and in which, Fig. 1 is a front elevation of the garment; Fig. 2 is a similar view showing the garment reversed; Fig. 3 is a similar view illustrating another face of the garment; Fig. 4 is a similar view showing the arrangement of Fig. 3 reversed to present the fourth face of the garment to the view of an observer; Fig. 5 is a sectional view taken along the line 5-5 of Fig. 1; Fig. 6 is a sectional view taken along the line 6-6 of Fig. 3; Fig. 7 is a detailed view, partly broken away, of the lower end portion of the front opening of the garment; Fig. 8 is a sectional view taken along the line 8-8 of Fig. 2; Fig. 9 is a sectional view taken along the line 9-9 of Fig. 2; Fig. 10 is an enlarged detailed view of a portion of the collar when the garment is in the condition shown in Fig. 1; Fig. 11 is a sectional view taken along the line 11-11 of Fig. 10; Fig. 12 is a sectional view taken along the line 12-12 of Fig. 10; Fig. 13 is an enlarged detailed view of a portion of the collar when the garment is in the condition shown in Fig. 3; Fig. 14 is a sectional view taken along the line 14-14 of Fig. 13; Fig. 15 is a sectional view taken along the line 15-15 of Fig. 1 and

2

Fig. 16 is an end elevational view of one of the cuffs of the garment.

The garment illustrated in the drawings is composed of two portions or sections which may interchangably be outer sections and whose four faces may each constitute the outer face of the garment at the option of the wearer. For the purposes of explanation, however, the section designated 1 in the drawings shall be considered the outer section of the garment and the section designated 2, the inner section. Likewise, the faces of section 1, designated 3 and 4, shall be considered the outer and inner faces, respectively, of such section, while the faces of section 2, designated 5 and 6, shall be considered the outer and inner faces, respectively, of such inner section. The outer face 3 of section 1 which is herein shown in the form of a jacket (note Fig. 1), may be composed of suede, or any suitable fabric material having a predetermined color or pattern. The other side or inner face 4 of the outer section 1 (see Fig. 3 of the drawings), is provided with a contrasting color, pattern or material so that when such side 4 is turned outwardly, the jacket will have an entirely different appearance. The sleeves 7 of such outer section are connected to the body thereof in such manner that finished seams are presented on both faces or sides of such section. The side and shoulder seams of section 1 are also finished on both faces of such section. Thus, section 1 will present a finished appearance whether the garment is worn with face 3 of section 1 outermost, as is shown in Fig. 1, or with face 4 of section 1 outermost, as is shown in Fig. 3 of the drawings. The outer ends or cuffs 8 of the sleeves 7 may be finished in any suitable manner to provide a finished appearance with relation to both faces 3 and 4 of section 1. In the garment illustrated, the cuffs 8 are each provided with a lengthwise opening which is closed by any suitable fastening means, such as the link 9 interengaging with buttonholes on each side of such opening, as is shown in Fig. 16 of the drawings. Pockets 10 and 11 may also be provided on the faces or sides 3 and 4, respectively, of section 1 and may be constructed by securing to the two faces of the section in overlapping relation, suitably shaped pocket pieces, as is shown more clearly in Fig. 15 of the drawings, wherein the pocket piece forming pocket 10 is designated 12, while the pocket piece forming pocket 11 is designated 13.

The inner section 2 of the garment is contained within section 1 and like the latter may have a jacket form, the same as, or different from the

form of section 1. The outer face 5 of section 2 which is shown in Fig. 4 of the drawings may be made of any suitable material having a color or pattern which contrasts from the outer and inner faces 3 and 4 of section 1 of the garment. The inner face or other side 6 of section 2 which is shown in Fig. 2 of the drawings, is made with a color, pattern or material which distinguishes from and is in contrast with the previously mentioned three faces 3, 4 and 5 of the garment. Like the seams of section 1, the seams on the sides, shoulders and sleeves of section 2 are constructed so that a finished appearance is provided whether the garment is worn with face 5 or face 6 of such section outermost and presented to the view of the observer. The sleeves of the section 2 are entirely disconnected from the sleeves of the first section, but the outer ends or cuffs thereof are preferably detachably coupled to the cuffs 8 of section 1 by suitable fastening means, such as the links 9 shown in Fig. 16 of the drawings. Suitable pockets may also be provided on the two faces 5 and 6 of section 2. In the construction shown in the drawings, the pockets for section 2 are each formed by cutting a horizontal slit in the material of section 2 and then folding the material along the lower edge of such slit to form the open, upper end 14 by which entrance is gained to the pocket when the face or side 5 of section 2 is worn outermost (note Fig. 9). Attached to the inner face of section 2 below the slit is a pocket piece 15 which forms the outside of the pocket when the face or side 6 of section 2 is worn outermost (note Figs. 2 and 9) and whose upper folded edge 16 (see Fig. 9) is free to permit entry into the pocket in such condition of the garment. Attached to the upper edge 17 of the slit is a flap 18 which overlies the upper edge 16 of the pocket piece 15 and a depending tab 19 provided with a buttonhole to interengage with a button 20 provided on the outer face 5 of section 2 below the pocket opening (compare Figs. 2, 4 and 9).

The bottom edges of sections 1 and 2 of the garment are free and disconnected throughout their entire lengths except in the regions thereof which form part of the front edges of the garment. The front edges of the two sections are provided with suitable complementary fastening devices, generally indicated by the numeral 21, for securing such edges together. The fastening device may comprise any one of the complementary fastening devices commonly used by the trade, but is preferably of the slide operated, separable fastener type modified to accomplish the purposes of the invention. As is shown more clearly in Figs. 5 to 8 of the drawings, the separable fastener includes a pair of stringer tapes 22, 22 each provided with two rows or series 23, 24 of interlocking elements, the series of elements 23 of said stringers being adapted to be brought into interlocking engagement or disengaged by means of a manually operated slider 25, and the series of elements 24 of such stringers being interlocked or disengaged by a manually operated slider 26. When the faces 5 and 6 of the garment are exposed, as is shown in Figs. 1 and 2, the series of elements 23, 23 are in opposed relation (note Fig. 5), in position to be operated by the slider 25, while the series of elements 24, 24 and the slider 26 are positioned intermediate the sections 1 and 2 of the garment out of view of an observer. When the garment is worn with the faces 4 or 5 thereof outermost, the position of the series and sliders are reversed (compare Figs. 1, 2 and 5 and

Figs. 3, 4 and 6). The sliders 25 and 26 are provided with pull tabs on both faces or plates so that they may readily be manipulated from both sides.

As is shown more clearly in Figs. 5 to 7 of the drawings, the stringers 22, 22 of the fastener are secured intermediate their widths to the front edges of both sections of the garment by centrally disposed, longitudinally extending lines of stitches designated 27, 27 in the drawings. In connecting said stringers to the garment, the front edges of the outer section 1 are folded inwardly against the inner face 4 thereof to provide longitudinally extending folded portions 28, 28 and the front edges of the inner section 2 are folded outwardly against the outer face 5 thereof to provide the longitudinally extending folded portions 29, 29. The width of the folded portions 28 and 29 are such that the outer folded edges thereof overlie a major portion of the front and rear surfaces of the series of interlocking elements 23, 23 so that when the fastener is closed, such folded edges will meet and effectively conceal the interlocked elements of the fastener (see Figs. 1, 2 and 5). Positioned intermediate the folded portions 28 of section 1 and the inner face 4 thereof, are folded strips of material 30, 30 whose folded edges overlie one face of the series of interlocking elements 24, 24 and are adapted to conceal such elements when the interlocking elements are interengaged and the garment is worn with the face 4 of section 1 outermost as is shown in Fig. 3 of the drawings. In a similar manner, folded strips 31, 31 are positioned intermediate the folded portions 29, 29 of section 2 and the outer face 5 thereof so that the folded edges of such strips overlie the outer faces of the interlocking elements 24 and effectively conceal them when the garment is worn with face 5 outermost, as is shown in Fig. 4 of the drawings. Strips 30, 30 are made of material similar to that of face 4 of the garment while strips 31, 31 are made of material similar to face 5 of the garment, so that such strips conform in appearance to such faces when exposed or outermost. The lines of stitches 27, 27 secure the several folds and strips to the stringers as is shown more clearly in Figs. 5 and 6 of the drawings.

The stringers 22, 22 of the separable fastener 21 extend upwardly to a point above the lines of juncture of the collar to the top edges of the sections 1 and 2 of the garment (note Figs. 10 and 13). The collar of the garment is composed of two layers of material, the side or faces 32, 34 of one layer having the same color, fabric or pattern that is possessed by the faces 3 and 4, respectively, and the sides or faces 33 and 35 of the other layer having the same color, fabric or pattern of the faces 6 and 5, respectively. The collar may be constructed by placing the two layers on each other with the faces 32 and 33 in opposed relation and connecting the two layers together by a line of stitches 36 which extends along the top and side of the collar closely adjacent to the top and side edges of such layers (note Figs. 10 to 12). The attached layers are then turned inside out so that the faces 32 and 33 are outermost and the ends thereof are each folded in to provide a fold 37 (not Fig. 11) which is triangularly-shaped and in the nature of a dart having its greatest width at the bottom of the collar. The lower end of the triangular fold or dart 37 is substantially equal in width to the width of the folded portions 28, 29 along the front edges of the garment. With the collar attached

to the sections 1 and 2 and the stringers 22, 22 in position, a second line of stitches 38 is applied to connect the two layers together from the upper ends of the lines of stitches 27 and around the three sides of the collar inwardly of the line of stitches 36. It will thus be seen that when the faces 32, 33 of the collar are outermost, the collar will have the finished appearance shown in Fig. 10 of the drawings, the size and shape of the collar being determined by the line of stitches 36 and the folds 37. When the faces 34 and 35 of the collar are outermost, the line of stitches 38 will determine the size and shape of the collar and the collar will have the finished appearance shown in Fig. 13 of the drawings. The layer of the collar having faces 33, 35 is secured to the upper edge of section 1, with face 33 thereof on the same side as face 3 of section 1 (note Figs. 11 and 12). The seam connecting this layer to section 1 is made so that it presents a finished appearance which ever side of section 1 is turned outermost. The layer of the collar having faces 32 and 34 is secured to the upper edge of section 2, with face 34 thereof on the same side as the outer face 5 of such section and face 32 thereof on the same side as face 6 of such section (note Figs. 10 to 13). The seam connecting this second layer of the collar to section 2 is likewise finished on both sides. As a result of this construction, it will be noted that when faces 32, 33 of the collar are outermost, the side or end edges of the collar will be flush with the folded edges of the folded portions 28, 29 overlying the stringers 22, 22, while when faces 34, 35 of the collar are outermost, the ends of the collar will not project beyond the lines of stitches 27, 38 and will be inwardly of the folded strips 30 and 31 (note Fig. 13).

It is believed that the construction of the compound shirt of this invention will be clear from the foregoing description. It is also believed to be clear from the foregoing that in the use of the garment, either section 1 or section 2 thereof may constitute the outermost section and that whichever section is outermost by reversing the garment as a unit another face thereof will be turned outermost. Thus if face 3 of section 1 is outermost, in the condition shown in Fig. 1 of the drawings, by reversing the garment as a unit, face 6 of section 2 will be turned outermost as shown in Fig. 2 of the drawings. Due to the above described arrangement of the collar, face 32 thereof attached to the upper edge of section 2 will match face 3 of section 1 when the collar is turned down and in the same condition of the collar, face 33 thereof attached to the upper edge of section 1 will match face 6 of section 2. When it is desired to wear the garment with either face 4 of section 1 or face 5 of section 2 outermost, this result can readily be attained by grasping the bottom edges of the two sections and separating the two sections so as to cause the four sleeves to be turned inside out and at the same time separated. The collar is then turned inside out and by grasping the ends of the collar, the two sections may readily be shaken to their reversed condition. Depending upon which face 4 or 5 is to be worn outermost, the sleeves of one section are inserted into the sleeves of the other. To bring the other face outermost, the garment is simply reversed as a unit.

While for the purposes of illustration a preferred embodiment of the invention has been shown and described, it will be understood by those in the art, that various changes and modi-

fications in such embodiment may be made without departing from the spirit of the invention or the scope of the appended claims.

I claim:

1. A reversible garment having a plurality of contrasting faces and comprising an inner portion having the form of a complete garment and an outer portion having the form of a complete garment, said inner and outer portions having a common reversible collar including two layers of material, one layer of which is connected along its bottom edge to the upper edge of said inner portion and the other layer of which is connected along its bottom edge to the upper edge of said outer portion, said layers being connected together along their top and end edges, means connecting one front edge of said inner and outer portions together and means connecting the other front edge of said portions together, complementary fastening devices for securing said front edges together when two faces of said portions are arranged in opposed relation and complementary fastening devices for securing said front edges together when the other two faces of said portions are arranged in opposed relation.
2. A reversible garment having a plurality of contrasting faces and comprising an inner section having the form of a complete garment and an outer section having the form of a complete garment, said inner and outer sections being disconnected along the bottom edges thereof and each being provided with sleeves disconnected from the sleeves of the other section, means connecting one front edge of said sections together and means connecting the other front edge of said sections together, a reversible collar common to both of said sections and including a layer connected along its bottom edge to the upper edge of one of said sections and a layer connected along its bottom edge to the upper edge of the other section, the top and end edges of said layers being connected together to provide a finished appearance whether the collar is in one condition or reversed, complementary fastening devices for securing said front edges together when one pair or the other two faces of said section are arranged in opposed relation.
3. A reversible garment having a plurality of contrasting faces and comprising an inner section having the form of a complete garment and an outer section having the form of a complete garment, said inner and outer sections being disconnected along the bottom edges thereof, a reversible collar common to both of said sections and including a layer connected along its bottom edge to the upper edge of one of said sections and a layer connected along its bottom edge to the upper edge of the other section, the top and end edges of said layers being connected together to provide a finished appearance whether the collar is in one condition or reversed, fastening devices provided on each pair of associated front edges of said sections, means connecting together each pair of associated front edges and the fastening devices thereon, the fastening devices on each pair of connected edges being complementary to the fastening devices on the other pair of connected edges and adapted to be interlocked to secure said paired connected edges together to close the front opening of the garment whether one pair of faces of said sections are arranged in opposed relation or whether the other two faces of said sections are arranged in opposed relation.
4. A reversible garment such as is defined in

claim 3, in which the said layers of said collar are connected along their top and side edges by an outer line of stitches defining one conformation of the collar and are connected along their top and side edges by a second line of stitches positioned inwardly in spaced relation to said first line of stitches and defining another conformation of the collar when the latter is reversed.

5. A reversible garment such as is defined in claim 3, in which the said layers of said collar are connected along their top and side edges by an outer line of stitches defining one conformation of the collar, and are connected along their top and side edges by a second line of stitches positioned inwardly in spaced relation to said first line of stitches and defining another conformation of the collar when the latter is reversed, the material of said layers along the side edges of said collar being folded inwardly towards said second line of stitches to provide a substantially triangularly-shaped stuck whose greatest width is adjacent to the bottom edges of said layers.

6. A reversible garment such as is defined in claim 3, in which said complementary fastening means comprises two rows of cooperating fastener elements projecting outwardly from the paired connected front edges of said sections, a slider constructed to interengage or disengage such elements upon manual movement thereof longitudinally of the rows, a second pair of rows of cooperating fastener elements projecting inwardly from the paired connected front edges of said sections and positioned intermediate the opposed faces thereof, and a second slider constructed to interengage or disengage said second pair of rows

of elements upon manual movement thereof longitudinally of the rows when the sections are arranged so that the latter project in opposed relation from the paired connected front edges of the sections.

7. A reversible garment such as defined in claim 3, in which said complementary fastening means comprises two rows of cooperating fastener elements projecting outwardly from the paired connected front edges of said sections and two rows of cooperating fastener elements projecting inwardly from said paired connected front edges and positioned intermediate the opposed faces of said sections, the front edges of said sections being folded to provide covering portions for one pair of cooperating rows of elements and to conceal the same in their interengaged condition, and covering strips overlapping the faces of the other pair of cooperating rows of elements and concealing the same in their interengaged condition, a slider for one pair of cooperating rows of elements and a slider for the other pair of cooperating rows of elements.
